UNITED STATES PATENT OFFICE.

HERBERT H. POWERS, OF LA GRANGE, ILLINOIS.

MEANS AND METHOD OF PREPARING PRINTING PLATES.

Application filed September 4, 1924. Serial No. 735,773.

The present invention relates to means and methods of preparing printing plates for treatment with suitable chemicals, such as etching and like substances.

- 5 In the art of printing with etched plates or the like, the preparation of the plate is easily effected by applying a sensitized layer upon which is placed a photo-negative through which is transmitted light or actinic rays for the transfer of the picture or like impression upon the sensitized surface of the plate. The latter is then suitably treated to fix the transfer and then the lines, areas and like parts thereof are treated with a 15 "resist" material, such as a resinous powder known as "dragon's blood", the powder adhering to the surface and sides of the lines and like parts to be protected. Heating the plate will fix or fuse the powder in place. 20 The remainder of the plate surface to which the powder does not adhere will be attacked or etched when the plate is placed in an etching bath, such as acid, the plates usually being of zinc, or zinc compositions, or copper and other like and similar substances. 25 The etching fluid will dissolve the unprotected surface parts of the plates to a certain depth and when cleaned and dried, may be again subjected to the dragon's blood powder treatment.

In applying the powder it has generally been done by covering the plate surface with the powder and brushing the powder, usually with a hand brush, across the surface of the plate in one direction. The larger percentage of the powder is brushed off the plate and the remainder is thus piled against one side of the lines or parts to be protected, as well as upon the surfaces of such lines or parts. The plate was then heated to fix or fuse the powder and then cooled in running water. The cooling in this way usually caused the plates to buckle or warp, the subsequent mechanical flattening of the plates 40 usually resulting in considerable waste. Then the plate, again by hand operations, was brushed with the powder in a direction transversely to that previously used and again heated and cooled. This was continued until the powder was applied four times in four different directions. Then the plate was placed in the etching bath. Further etchings or "bites" were made depending upon the depth of material to be removed, 45 was obtained, each "bite" or etching treat-

ment being alternated with the previous four brushings and heatings, and subsequent coolings.

Such a process required a large amount of time, much handling by the operator, the results depending upon and varying with the efficiency of the operator and involved considerable waste of powder, which sells at a very high price, and with the attendant adhering and collecting of the powder to and upon the clothes and person of the operator, such as in his eyes, mouth, ears, hair, lungs and other respiratory organs. The powder would also spread about the shop, room or the like and collect upon about everything in the vicinity.

The brushing of the powder so that it will pile against the sides of the lines and parts to be protected, very much like snow drifts against a fence or wall, requires considerable ingenuity and it is impossible, in manual operations, with a brush, to apply the correct amount of powder and obtain uniform results, the piling generally being too little or too great and the consequence being a more or less irregular and inclined side wall to the line or area to be protected. Moreover, there generally always remain stray particles of powder on the parts to be etched out, which cause pin points and the like. To remove these requires the mechanical operation of gouging and rabbeting with suitable gouging and rabbeting tools.

By the present invention the operations are carried out mechanically, preferably in a unitary machine, and the powder is confined to the spaces or zones of operation or treatment without any loss of the powder or spreading about thereof. The application of the powder is effected in the most efficient manner and at the proper angle to produce the piling of the correct amount against the sides of the lines or areas to be protected, so that when the etching is completed, the side walls are regular and clean-cut, and are perpendicular to the surface of the plate. By the use of suitable means, such as a brush, the stray and residual particles may be removed at the out-set, before "fixing", thus eliminating the subsequent operation of gouging and rabbeting, etc. The powder is preferably applied to the surface of the plate at an angle such that the proper amount of powder will pile against the sides of the lines and areas to be protected, and the

surplus powder will be forcibly cast from the plate and carried away, this being preferably done pneumatically. The "fixing" is effected by heating only the powder left on the surface of the plate without any substantial heating of the surface portions of the plate and without any heating of the body portion of the plate itself. This results in greatly reducing the time of heating as well as that of the subsequent cooling, and also the complete elimination of buckling and warping of plates and the attendant waste thereof. The cooling is preferably effected by a stream of air, although other fluids may be used if desired. Inasmuch as the plate has not been heated, but only the powder on the surface thereof, little cooling is necessary, and the return of the plates to be powdered for transverse piling, is accordingly hastened.

The powder is preferably circulated in a way such that the powder not used on the plate is immediately drawn away and conveyed to a collecting reservoir where it may be distributed, rather than piled up in a single pile, by suitable means, such as baffles and means may be provided for ready release of the air utilized to convey the material to the reservoir, such as through pervious pockets or cells. Since the powder has the characteristic of adhering tightly to objects with which it contacts, the pervious means may soon clog and to avoid this, the pockets or cells may be made to vibrate, as by allowing them to contract and then suddenly stretching them taut so as to snap the powder from the surfaces thereof, the powder then falling into the lower part of the reservoir. This is only necessary at infrequent intervals and may be effected by hand operated mechanism, although power operated means are comprehended by the invention for the purpose of accomplishing the desired results. The collected powder may also be stirred, preferably continually to prevent the packing and to be in condition for the pneumatic conveying of it to the powdering zone when the control mechanism is operated, such as the valve in a conduit leading from the reservoir to a blower and projecting nozzle, the latter being of utility to direct the air and powder upon the surface of the plate at the angle requisite to effect the proper piling of the powder against the sides of the parts to be protected.

The fixing or fusing of the powder on the plate is by way of heating, and preferably in a heating chamber with the heating means, such as burners, located above and suitably proximate to the surface of the plate when it is located in or moved into the chamber. To economize fuel supply, the heater may have a pilot light and the main supply may have a control valve capable of operation

by the means carrying the plate into and out of the heater, to open and close the valve respectively, the pilot acting to ignite the burners when the fuel is turned on and the plate is in the heater. To assure good combustion, air may be supplied through a valve controlled conduit into the upper part of the heater, the latter being preferably provided at its lower part, as at the sides thereof, with openings for the free exit of the products of combustion. The heat is preferably applied downwardly against the surface of the plate rather than upwardly through the plate.

In the cooling zone the means for supplying the air to the powdering zone and for exhausting the surplus of powder therefrom, may be constructed with valve controlled passages and operating mechanism for the valves for automatically effecting the flow of cooling air upon the plate after leaving and before moving to the powdering zone or chamber, the means carrying the plate being preferably provided with means, such as spring pressed cam-pawl or similar elements, for actuating the valve operating mechanism when the means for carrying the plate is moved.

Inasmuch as the powder is applied first in one direction across the surface of the plate, and then in a direction transverse to the former direction or at right angles thereto, until the powder has been applied in four directions, the means for carrying the plate is preferably provided with a turntable or the like with mechanism on the table and the support of the machine, cooperable to give the table a quarter turn between the powdering operations, this being done preferably after the fixing or fusing of the powder in the heater and as the plate is leaving the heating device, although it may occur at any other point of movement of the carriage and the plate, as for example, just before entering the heater or just before entering the powdering zone or chamber.

The invention also comprehends other objects, advantages, and capabilities, as will later appear and are inherently possessed by the invention, it being understood that the specific device herein described and shown upon the drawing, is merely illustrative of the invention, the latter not being limited to the specific disclosure made but comprehending other details, arrangements of parts and constructions without departing from the spirit of the invention.

In the drawings, illustrating an embodiment of the invention, Fig. 1 is a view in side elevation of a machine constructed in accordance with the invention: Fig. 2 is a top plan view of the same; Fig. 3 is a top plan view of a plate carriage and turntable, with parts of the powdering chamber in fragmentary section and also showing,

diagrammatically, the automatic means and operation for turning the turn table a quarter turn; Figs. 4, 5 and 6 are fragmentary sectional views of the carriage and turn-table; Fig. 7 is a longitudinal vertical section through the powder collecting reservoir and the powdering chamber; Fig. 8 is a transverse sectional view of the collecting reservoir; Fig. 9 is a detailed view, 10 partly in section, of one of the pockets or cells of the collecting reservoir; Fig. 10 is a longitudinal sectional view of part of the powdering means and powder cleaning device; Fig. 11 is a perspective view, partly 15 in section and partly in diagram of the valve control mechanism and the means on the carriage for actuating the same; and, Figs. 12 and 13 are respectively top plan and side elevational views of the latch for causing 20 the quarter turn of the turn table.

Referring now more particularly to the drawings, the embodiment chosen to illustrate the invention is shown as comprising a supporting frame or support 1 having legs 25 2 carried on casters 3 and provided with sheet metal side and end panels 4. Upon the top 5 of the support, which may also be of sheet metal, are located and secured a pair of rails 6 over and along which is capable 30 of traveling a carriage 7 having wheels 8 arranged and adapted to operate on the rails 6. The carriage is capable of moving from one end of the machine to the other end thereof along the rails as clearly shown 35 in Figs. 1, 2 and 3 of the drawings.

To the ends of the carriage 7 are secured the ends of a cable or rope 9 capable of passing over pulleys 10 and 11 rotatably mounted in brackets 12 and 13 secured, in any suitable 40 manner, to one end of the support 1, and over another pulley 14 rotatably supported in a bracket 15 secured to the other end of the support 1, as clearly shown in Figs. 1 and 2 of the drawings. The cable 45 continues about a hand operated drum 16 carried by a shaft 17 rotatably mounted in a side wall 4 of the support and to the outer end of which shaft is secured a hand wheel 18 provided with a handle 19 by which the 50 hand wheel and drum 16 may be rotated as desired. The cable 9 preferably has one or more turns about the drum whereby traction may be effected. From the above construction it will be apparent that the carriage 55 may be caused to travel along the rail, as for example, from the left to the right hand end of the machine by a right hand rotation of the hand wheel 18 and drum 16, and a travel of the carriage from the right hand end of 60 the machine to the left hand end thereof by a left hand rotation of the wheel and drum.

The carriage 7 is preferably made of sheet metal and hollow and arranged to receive a rotating turn-table 20 carrying a grating 21 65 at the upper end of the turn-table and upon

which a plate, to be treated, may be placed. The turn-table is provided, at several points arranged in a circle, with wheels or rollers 22 each having a tire portion 23 and a flange portion 24 bearing respectively laterally and 70 downwardly against a race-way portion or track 25 formed in the lower wall 26 of the carriage 7. The race-way or track portion 25 is preferably circular and the wheels 22 are preferably provided with axles 27 being 75 rotatably mounted in the turn-table 20 so as to support the same for rotation in the carriage about a vertical axis and also to substantially present the top surface of the turn-table level or even with the top surface of the 80 carriage 7, as clearly shown in Figs. 3, 4, 5 and 6 of the drawings. At suitable points along the periphery 28 of the turn-table are provided a number of recesses or depressions 29, preferably at 90 degrees apart, and into 85 which may engage a ball 30 normally pressed into place by a spring 31 included in a cap 32 secured to a side wall 33 of the carriage 7. When the turn-table is rotated, as for example a quarter turn, one of the 90 depressions 29 will arrive opposite the spring pressed ball 30 so that the latter will enter into the recess or depression 29 and normally resiliently lock or hold the turn-table from further rotation, yet not 95 preventing the forcible rotation of the table when it becomes desirable to do so, which will be later more fully explained. See Fig. 6 of the drawings.

At each time that the carriage is caused 100 to move from the left hand to the right hand end of the machine and then return to its original position, means is provided to cause an automatic turning of the turn-table a quarter turn so that the plate carried upon 105 the grate 21 may be presented for movement and treatment in a direction transverse to or at right angle to its previous movement and treatment. This turning of the table is effected by a latch arrangement 34 located 110 near one of the rails 6, see Fig. 3 of the drawings, and which is shown in detail in Figs. 12 and 13 of the drawings. This latch arrangement has a base member 35 suitably secured to the top 5 of the support near the front rail 6 of the device and has a bearing member 36 carrying a pivot bolt 37 to which is rotatably mounted a cam lever 38 having a cam surface 39 and a cam slot 40 of generally S or Z-shape and having lateral openings or throats 41 and 42 as clearly shown in Fig. 12 of the drawings. The cam portion 38 is normally held in upper or horizontal position by a spring 43 reacting between the members 38 and 35, as clearly 115 shown in Fig. 13 of the drawings. Cooperating with this cam are pins 44 connected to the bottom of the turn-table 20 at four different points and arranged in a circular path when the turn-table is rotated. The pos- 120 125 130

tions of these pins are designated by characters A, B, C and D, as referring to the first, second, third and fourth pins in their relative positions as they are operated upon by the cam device 34 and as shown in their different positions in dotted lines in Fig. 3 of the drawings. When the turn-table is located so that the spring pressed ball 30 is properly located in one of the recesses 29, the pins A, B, C and D will be in the positions shown at the left hand end of Fig. 3 and designated by the characters A, B, C and D. Upon moving the carriage to the right the pins D and A will successively engage with a beveled or inclined face 45 on the upper member 39 of the cam mechanism or latch 34 and will cause the cam member 38 to be depressed against the compression of the spring 43, thus permitting the carriage to pass on to the right hand end of the machine without any turning effect of the turn-table. When the carriage is caused to move in a reverse direction the pin A will first contact with the inner end of the cam surface 39 at substantially the point 46 as shown in Fig. 12, and further movement of the carriage will cause the pin A to travel along the surface 39 toward the throat 41 thus simultaneously causing a rotation of the turn-table about its axis. Further movement of the carriage will cause the pin to enter the throat 41 and into the slot 40 and then travel along the slot 40 toward the throat 42 and then out of throat 42. At this time the pin A has now taken the former position of pin D and pin D the former position of pin C and so on about the circle. The successive positions of the pins and the turn-table are diagrammatically shown in dotted lines, in Fig. 3 of the drawings. The position 47 shows the turn-table before the pin A engages with the cam; the position 48 showing the position of the turn-table just as the pin A engages with the cam surface 39; the position 49 showing the same when the pin A is entering the throat 41 and the position 50 showing the same when the pin A is leaving the throat 42 and when the pin B has assumed the position that pin A formerly had. Further movement of the carriage to the left will not turn the turn-table, but as the pin reaches the throat 42 and about to leave it, the turn-table shall have turned with a depression 29 opposite the spring press ball 30 so that the latter will spring into it and normally hold the turn-table in its new and turned position.

At the left hand end of the machine and upon the top 5 is arranged a powdering chamber or zone in the form of a closed casing into which the carriage may travel. This casing has side walls 51 and 52 and a top having an opening normally closed by a door 53 provided with a transparency 65 through which one may inspect the interior

of the casing. The left hand end of the casing tapers to form an outlet 54 connected with an intake 55 of an exhaust blower or pump 56 operated by a motor 57 suitably connected to the pump to operate it at a high speed. The pump has a discharge conduit 58 leading downwardly and then laterally into an end of a collecting reservoir 59 arranged beneath the top 5 of the machine. The other end 52' of the casing is provided with an opening 60 through which the carriage 7 may enter into or pass from the casing. To this end 52' of the casing are also secured supporting brackets 61 having bearings 61a for supporting pintles 62 of bell-crank arms 63. To an end of the arms 63 is rotatably mounted a brush 64 by means of shaft 65. The other end of the arms 63 extend upwardly and carry adjusting screws 66 threaded through portions 67 with the end of the screws engaging with cam surfaces 68 supported upon or forming flanged portions on an upwardly extending part 69 of the brackets 61, all as clearly shown in Fig. 10 of the drawings. By loosening the screws 66 the arms 63 may be moved so as to raise or lower the brush 64 toward or from the surface of the plate carried on the carriage traveling beneath the brush. When in the adjusted position the screws 66 may be tightened against the cam surfaces 68 so as to hold the brush in desired position. Also extending through the opening 60 is the lower end or nozzle portion of a powder discharge 70 having a narrow elongated slot or orifice 71 capable of discharging air and powder at an acute angle to the surface of the plate resting upon the carriage 7, as clearly shown in Fig. 10 of the drawings. Overhanging the orifice 71 is preferably provided a lip or flange 72 for confining the stream of powder and air projected from the orifice to the space immediately above the surface of the plate carried by the carriage 7. The nozzle 70 is preferably supported in adjusted position by means of brackets 70' having flanges secured to the top of the nozzle 70, and slotted arms adjustably secured to the end wall 52' of the chamber or casing, by means of suitable bolts extending through the slots of the bracket arms. By loosening the bolts the brackets 70' together with the nozzle 70 may be adjusted as to height, and then when the bolts are tightened the nozzle, together with the brackets, will be held in adjusted position. The lip may be provided with a bead 73 for reinforcement. An electric light 74 may be located above the transparent door 53 so as to transmit light within the interior of the casing.

Over the top 5 and intermediate the ends of the machine is located a blower plant comprising a pair of blowers 75 and 76 mounted upon a common shaft with and

driven by a motor 77; the motor and the blowers being, as a unit, supported upon a stand comprising legs 78 at both sides of the machine and connected horizontal members 79 and 80, the lower ends of the legs 78 being suitably secured or fixed to the frame 1 of the machine. The blower 75 discharges into a conduit 81 flaring into a wide nozzle 70 in which is provided 5 the drawings) which in one position will open the passage of air to the nozzle 89 and close the passage of air through the discharge 98, and in another position will cut off the flow of air into the nozzle 89 and open up 70 the passage through the discharge nozzle 98. The valve 99 is secured to a shaft 100 supported at the outer end thereof in a bracket 101 secured to one of the legs 78 of the stand upon which the blower plant is 75 supported. To this shaft is fixed an arm 102 carrying a pin 103 against which may operate or contact a spring pressed pawl or cam member 104 pivotally connected to a bracket 105 secured to the top of the carriage 7. The pawl has a spring 106 reacting against the face of the brackets 105 and an arm 107 of the pawl to normally hold it in upright position, the pawl being limited 80 in movement by a stop arm 108 normally bearing against the top surface of the carriage 7 as clearly shown in Fig. 11 of the drawings. When the table is moved in one direction, as from the powdering to the heating zones, the cam 104 will engage with 85 the pin 103 to be rocked and compress the spring 106, the table and pawl passing on without operating the valve mechanism connected to the arm 102 and pin 103, but when the carriage 7 is moved in the opposite 90 direction the pawl 104 engages the pin 103, and by reason of the limit stop 108 bearing against the top surface of the carriage 7, and thus hold the pawl 104 in fixed position, the pawl 104 will effect a movement 95 of the pin 103 together with the arm 102 and shaft 100 so as to operate the valve 99 from a position where it closes the nozzle 89 to a position where it closes the discharge 98 and opens the nozzle 87. 100

The shaft 100 also has secured to it an arm 109 slotted to receive a pin 110 connected to a bell crank lever 111 rotatably supported upon a projecting portion 112 of the bracket 101 and provided with a depending arm 113 110 carrying a contact pin 114. This pin 114 is operated on by a pawl 115 of the same construction as pawl 104, it comprising an arm 116 against which reacts a spring 117 bearing against the base of a bracket 118 secured 115 to the top surface of the carriage 7 but laterally out of alignment with the pawl arrangement 104. The pawl 113 also has a stop or limiting arm 119 normally bearing against the top surface of the carriage 7. 120 When the carriage is moved in one direction, the arm or pawl 115 will engage with the pin 114 and be moved, while compressing the spring 117, to pass by the pin 114 without 125 effecting any movement of the arm 113 and the parts connected to it, but when the carriage is moved in an opposite direction the pin 115 engages the pin 114 and by reason of the limit arm 119 bearing against the top surface of the carriage 7, will effect a 130

10 15 20 25 30 35 40 45 50 55 60 65 70 75 80 85 90 95 100 105 110 115 120 125 130

For the purpose of driving the brush 64 the shaft 65 of it is connected through suitable gearing 94 to a shaft 96 connected in 50 turn to suitable gearing 97 to the outer end of the shaft of the motor 77, the drive being effected from the motor shaft to the brush as clearly shown in Figs. 1 and 2 of the drawings. The discharge conduit 88 of the 55 pump or blower 76 is preferably provided with a branch outlet 98 for directing a stream of air downwardly upon the plate carried by the carriage 7, when the latter is in position underneath the discharge outlet 98. The purpose of this is for projecting 60 cooling air upon the surface of the plate after the same has been heated and moved from the heating apparatus. The passage of air through the outlet 98 or to the nozzle 89 is controlled by a valve 99 (see Fig. 11 of

movement of the pin 114 together with the arm 113 and the pin 110 upwardly to swing the arm 109 upwardly and turn the shaft 100 so as to swing the valve 99 from its closing position with reference to the discharge 98 to a closing position with reference to the nozzle 89.

At the right hand end of the machine is located a heating device comprising preferably a sheet metal casing 120 closed at the top and opened at the bottom and spaced from the top 5 of the support and supported by legs 121 suitably secured to the sides of the casing 120 and the side walls of the support 1. In the upper part of the casing 120 are located a plurality of gas burners 123 connected to a main 124, each burner being individually controlled by hand operated valves 125, the valves 125 being also provided with suitable air regulating devices 126 as is usual. The main 124 extends about the end of the machine and is provided with a spring operated valve 126 having a lever 127 arranged to extend within the space of the heating device and in the path of movement of the carriage 7, such that when the carriage 7 has been moved to the right hand end of the machine, the end wall of the carriage may engage with the lever 127 and cause it to move from the position shown in full lines thereof to the position shown in dotted lines thereof in Fig. 2 of the drawings, whereby the valve 126 will be opened. When the carriage 7 is moved away from the right hand end of the machine, the valve 126 will be closed automatically by a spring surrounding the stem of the valve and return the lever or arm 127 from the dotted line position to the full line position thereof in Fig. 2 of the drawings. In this way the gas may be turned on or turned off automatically when the carriage arrives or is moved from the heating device and thus economize the fuel by preventing the combustion of the fuel to the full extent at all times. From the main 124 leads a pilot tube 128 provided with a number of pilot burners or orifices 129 for providing pilot flames within the chamber. This flame is normally lighted at all times, and when the fuel or gas supply is conveyed to the burners 103, the pilot flames will ignite the same so that the burners may operate at full load during the time the carriage and plate is in the burner chamber. At the upper part of the chamber 120 is located an air inlet tube 130 communicating at one end thereof with the upper space of the chamber 120, and extending beneath the blower plant 10 and having a flared opening 131 at its other end for the intake of air from a stream passing upwardly through an opening or screened port 132 formed in the top 5 of the table support of the machine. The screened opening 132 communicates with the upper

part of the powder collector and is an outlet for the compressed air in the collector when the same is operated to bring the powder therein. The stream of air passing through the screened opening 132 will be directed to the opening 131 and pass through the conduit 130 into the heating chamber to supply air or other supporter of combustion to the burners therein. The heated air in the chamber 120 as well as the radiant heat from the burners will be directed downwardly toward the plate carried upon the carriage and over the surface of the same and out through the space between the chamber 120 and the top surface 5 of the machine, thus affording a free and ready outlet for the products of combustion at all sides of the heating device. In order to prevent the downward flow of the heated gases or the like passing through the grid or grating 21, especially when treating small plates, and heating the carriage parts, a plate or sheet 121' of heat insulating material, such as asbestos, is supported in a horizontal position in the lower part of the heating device, 90 by legs 121^a fastened to the top 5. The board or plate 121' is held as close to the bottom of the carriage as possible when the carriage is in the heating zone. This restricts the possible passage of the hot gases through the narrow space between the board or plate 121' and the bottom of the carriage, and hence the hot gases will freely pass from the surface of the carriage laterally through the wide openings between top of the carriage and the lower edges of the side and end walls of the hood 120.

The conduit 130 is preferably provided with a butterfly valve 133 upon a shaft 133^a connected to a controlling arm 133^b connected by a link or rod 134 pivotally connected to an arm 135 rigidly secured to the shaft 100. When the shaft 100 is operated or turned at the time of operating the valve 99, it will also operate, through the link 134, the valve 133 to open and close the same at the proper instant of operation of the device which will be more fully explained later.

Referring to the feed device at the bottom of the powder collector, the valve 85 is operated by an arm 136 connected to an arm 137 fastened to a shaft 138 operatively connected to a rod 139 connected to a hand lever 140 arranged at the front of the machine and at ready access of the operator. By operating the hand lever 140 the butterfly valve 85 may be thrown open and the powder in the end 86 of the feed tube 87 may be drawn into the conduit 83 by the suction produced by the fan blower 75 and hence the powder will be drawn therethrough and projected through the nozzle or orifice 71 of the powdering device into the powdering chamber or zone where the plate is to be

originally treated. For the purpose of preventing the accumulation and clogging of powder in the conduit 83, and to permit of the clearing of the passage therein of the powder at the time when the butterfly valve 85 is closed, the conduit is provided with an inwardly opening check-valve 83^a normally having the valve seated by a spring 83^b of given tension or compression, such that when the valve 85 is opened the pressure of the air in the tube 85 and the suction in the conduit 83 are such as to permit the valve 83^a to remain closed but when the valve 85 is closed, the suction in the conduit 83 will effect an opening of the valve 83^a and the entry of atmospheric air into the passage 83 and the pump 75, so also nozzle 70, so as to clear the passages thereof of all dust that may be therein at the instant of the closing of the valve 85. By having such passages neat and clean, there will not be projected clogs or lumps of powder from the nozzle 70 when next opening the valve 85 and operating the pump 75, but the powder will be drawn from the conveyor part 86 and supplied to the plate from the nozzle 70 in proper suspended and distributed condition.

From the above it will be noted that the powder is circulated through the machine and is confined therein so that it will not spread about the vicinity of the machine, the powder first passing from the feeding part of the collector through the blower and nozzle into the powdering chamber and then the surplus thereof exhausted through the suction blower and returned into the collecting reservoir. The latter is shown more specifically in Figs. 7, 8 and 9 of the drawings and as provided at its upper part with a plurality of cells or pockets 141 of pervious material such as cloth, canvas and the like through which air may pass but which will be of such a mesh or weave as to prevent the passage of the powder. Each pocket is preferably in the form of a tube or cylinder having an end thereof secured to a ring 142 fastened to the rim of an opening in the wall 143 of the collecting reservoir 59, and the upper end of the pocket being secured to a ring 144 carrying a conical pervious portion 145 secured at the apex thereof to a ring or eye 146. Each eye 146 is connected by a link 147 to a bell crank lever 148 pivotally supported upon cross-shafts 149 rotatably supported in the side walls 150 of the upper part of the collecting device. Each shaft 149 has a crank arm 151 secured thereto and pivotally connected at the free ends of the arms 151 to a horizontal shaker bar 152, the latter extending outwardly of the machine at one end thereof and being pivotally connected to a lever 153 carrying a handle 154. The operator may operate the lever 153 by means of the handle 154 and cause a longitudinal operation of the shaker bar 152 and

hence an up and down movement of the arms 148 and hence the upper ends of the pockets. This will first cause a contraction of the pockets and then when the levers or arms 148 are moved upwardly, so as to give the pockets 70 a taut stretch, the powder adhering to the inner walls of the pockets will be snapped therefrom and caused to drop into the lower part of the collecting reservoir. These pockets are arranged in plurality and at the 75 upper part of the collecting reservoir so that as the powder and air are forced into the reservoir the air may proceed upwardly through the pockets and pass therethrough into the upper chamber portion 155 and 80 thence through the screened outlet 132, the air thus passing out being free of powder. The stream of air passing through the screened outlet 132 is of utility for supporting combustion in the heating device as above 85 described. The collecting reservoir is preferably supported by means of supporting brackets 156 secured to the top 5 of the device and held in position as clearly shown in Figs. 7, 8 and 9. 90

As the powder and air is projected through the passage 58 into an end of the collector chamber 59, if no means were provided to prevent it, the powder would be projected to the other end of the collecting reservoir and packed into a single pile, with an uneven distribution of the powder. The powder would probably accumulate to the extent of clogging the entry to some of the pockets 141. In order to aid or serve in distributing the powder throughout the collector, the latter is provided at the lower part thereof with one or more baffles 157 and 158 so arranged that when the stream of air and powder is directed longitudinally through the upper 105 part of the collecting receptacle, the same will impinge against the upper part of the baffles so as to cause a whirling or spreading of clouds of the powder so the same will settle into the lower portion or legs 159, 160 110 and 161 in more or less even level. While the powder is settling the air is passing upwardly through the various pockets 141 and to the exterior through the outlet 132. The legs 159, 160 and 161 are opened at the lower ends thereof and communicate with the feed tube 87. In this feed tube 87 is located a spiral or helical feed screw 162 operated by gear mechanism 163 operatively connected to a shaft 164, connected to gear mechanism 165 operatively connected with the shaft of the motor 57, connected to the pump 56. The tube 87 may also be provided with a hopper 166 through which additional powder may be supplied to the feed tube 88, the hopper 166, being normally closed by a cap 167. The screw 162 is operative, when it is rotated, to gradually feed the powder toward the right end of the tube, as viewed in Fig. 7 of the drawings, and toward the valve 85 130

which controls the feed of the powder to the exhaust or drawing tube 83 leading to the powdering floor 75. In order to prevent the powder from packing so that it could not be 5 readily drawn by the suction produced in the passage 83 and the end 86 of the tube, the screw shaft is provided, in the tube 87, with reversed inclined scroll portions 168 operating with a tendency to feed the powder 10 backward but being few in number will not be sufficient to totally counteract the feeding action of the remainder of the screw. The portions 168 are preferably provided with a number of notches 169 for the passage 15 of the powder to the valve 85. In this way the powder is thoroughly stirred and prevented from packing or caking so that it will be in proper and fit condition to be easily drawn by the air passing through the valve 20 valve 85, when the latter is opened, and to the intake of the suction blower 75 and hence to the nozzle 70.

The motors are preferably operated electrically through a switch box 170 in which 25 may be also located a rheostat and from which lead the conductors through the sheathing 171 passing through pipe 172 and sheathing 173, the latter including the conductors to the motor 57 and the sheathing 30 171 having conductors 174 leading to the motor 77. A tube 175 for conducting the conductors of the lamp as well as supporting the same may be connected as shown in Fig. 2 of the drawings, and the inlet conductors 35 176 may carry the current to the switch and motors as well as the lamp.

In the operation of the device and with the carriage in the powdering chamber, a plate, to be treated, is placed upon the grate 21 and 40 then the rheostat is operated so as to start the motors, which will start to operate simultaneously, and then the operator will operate the hand lever 140 so as to open the butterfly valve 85 whereby the suction blower 45 75 will draw powder through the conduit 83 and project the same through the nozzle 70 at an acute angle to the surface of the plate. At the same time the operator will operate or rotate the wheel 18 and drum 16 together 50 with the rope 9 so as to cause the carriage with the plate to move to the right, as viewed in Fig. 1 of the drawings, so that the surface of the plate will gradually pass underneath the stream or sheet of powder being 55 projected from the nozzle or orifice 71 upon the surface of the plate. By locating the nozzle 70 at the proper angle with reference to the surface of the plate and regulating the pressure of air from the blower, the powder 60 may be projected upon the side walls or ridges of the raised portions of the plate at the proper angle to pack or pile the powder to give the best effect when the plate is later treated by etching in the etching bath. The 65 surplus powder will be thrown about into

the chamber and will be rapidly or quickly drawn out by the exhaust blower 56 and returned into the collecting reservoir 59, where the powder may settle and the surplus air pass through the pockets and through the 70 opening 132.

As the carriage proceeds to the right, the rotating brush 64 will have a very light contact with the surface of the plate for the purpose of removing all stray and foreign particles which might finally produce pin points and the like. These particles adhere to the bristles of the brush and are carried upwardly toward the nozzle 89. Air at that time is being projected from the orifice 90 75 and will remove the adhering particles and project the same into the lower part of the powdering chamber and be drawn through the exhaust blower 57 and returned into the collecting reservoir 59. As the carriage proceeds beneath the discharge outlet 98, the latter is in closed position at this time so that no air can pass downwardly there-through and destroy the piling of the powder on the plates. The carriage then next 80 proceeds into the heating chamber 120. As it arrives at the end of its throw or movement of the right hand of the machine, the right hand side of the carriage 7 will engage with the lever 127 and cause the same 85 to move into the dotted line position shown in Fig. 2 of the drawings and open the valve of the fuel conduit. The gas or fuel would then proceed to the burners and be ignited by the pilot flames and immediately heat the 90 surface of the plate. The effect of the heat is to merely heat the powder or fuse the same upon the surface of the plate without materially heating the surface portion of the plate and without any heating of the body 95 portion of the plate. At the same time the air that is blown through the opening 132 will pass into the conduit 130 and into the upper part of the chamber 120 for supplying 100 supporter of combustion and causing the heated gases to pass downwardly against the surface of the plate and out through the lateral openings beneath the chamber 120. In the meanwhile the operator has operated the arm 140 so as to close the valve 85 and prevent further projection of the powder into the powdering zone or chamber. As the carriage was moved to the right, both pawl cams 104 and 115 operated idly by slipping 105 by the pins 103 and 114. It will be noted 110 that in Fig. 11, the valve 99 is shown in the position for closing off the discharge 98. 115

The operator will now rotate the hand wheel 18 in a reverse direction so as to cause the carriage to travel toward the left. The 120 first movement of the carriage will effect the release of the arm 127 so as to permit the spring of the valve 126 to close off the fuel 125 in the burners. As the carriage proceeds to the left, a pin 44, such as that designated by 130

the character A in Fig. 3 of the drawings, will contact with the cam surface 39 of the cam latch and ride along this surface to the throat 41 and then into the groove 40 and out of the throat 42, thus causing a quarter turn of the turn-table in the carriage. It will be noted that when the carriage had been moved toward the right, the pin 44 had engaged with the inclined surface 45 so as to 10 depress the latch mechanism 34 without any action to turn the turn-table. With the turn-table now turned at 90 degrees from its previous position, it will be noted that the plate will now be presented to the nozzle or orifice 71 at 90 degrees to its previous presentation so that the powder may now be piled against the lines or ridges at right angles to the direction of previously piling the powder.

20 As the carriage proceeds from the heating chamber into the space between it and the powdering chamber and beneath the blower plant, the pawl 115 will first engage with the pin 114 and operate the valve mechanism so that the valve 99 will open the discharge passage 98 and close the discharge nozzle 89 and at the same time will close the valve 133 in the passage 130, so as to prevent any back-flow of hot air from the heating chamber 25 through the opening 131 toward the plate. By opening the passage 98, the blower 76 will discharge cold air through this opening upon the top surface of the plate and will cool the same, particularly the fused powder thereon. As the carriage still proceeds further, the cam member 104 will then engage with the pin 103, it being in a position to engage the same by reason of its previously having been moved with the shaft 30 when turned by the operation of the cam 115 against the pin 114. The engagement of the pawl 104 with the pin 103 will operate the valve mechanism to the position shown in Fig. 11 so as to close the discharge opening 98 and open the passage through the nozzle 89 and again open the passage 130 to the heating chamber. Further movement of the carriage will bring it into the powdering chamber where the operator may again powder the plate as in the previous case. The time consumed in performing these operations is much shorter than that heretofore required when hand operations were required. It will be noted that when the plate 45 now enters into the powdering chamber it has been turned 90 degrees from its previous position so that the powder from the nozzle 70 may be projected upon the ridges, lines and areas of the plate, to be protected, in a direction transverse to the previous direction of powdering. The operation will be carried on in this way until the plate has been powdered from four different directions. After this the plate may be removed to the 50 etching bath and the unprotected parts of the

plate removed or etched to the desired depth. If the depth is not sufficient, the plate may again be returned to the machine and powdered as before and again returned to the etching bath for a deeper etching or bite. 70

Having thus described my invention, I claim:

1. A device for preparing printing plates, comprising a powdering means, a heating means, and a movable means for carrying the plate to be treated from the powdering means to the heating means, said heating means being constructed and arranged to apply heat to the powdered surface of the plate, said heating means having means 75 cooperable with the movable means for supplying heat when the movable means has moved into the heating means and for cutting off the heat supply when the movable means starts moving from the heating means. 80

2. A device for preparing printing plates comprising a powdering means, a heating means, and a movable means for carrying the plate to be treated from the powdering means to the heating means, said heating 90 means being constructed and arranged to apply heat to the powdered surface of the plate, said powdering means having means for exhausting surplus powder from the vicinity of said plate. 95

3. In a device for preparing printing plates, a powdering device comprising means for blowing a resist powder against the surface of the plate and at an angle thereto, and means for moving the plate relative to the blowing means for progressive powdering across the face of the plate. 100

4. In a device for preparing printing plates, a powdering device comprising means for blowing a resist powder against the surface of the plate and at an angle thereto, means for moving the plate relative to the blowing means for progressive powdering across the face of the plate, and means for removing surplus powder from the plate. 110

5. In a device for preparing printing plates, a powdering device comprising means for blowing a resist powder against the surface of the plate and at an angle thereto, means for moving the plate relative to the blowing means for progressive powdering across the face of the plate, and means for fixing to the surface of the plate the powder remaining upon the plate. 115

6. In a device for preparing printing plates, a powdering device comprising means for blowing a resist powder against the surface of the plate and at an angle thereto, means for moving the plate relative to the blowing means for progressive powdering across the face of the plate, and a rotary brush for removing surplus powder from the surface of the plate. 120

7. In a device for preparing printing plates, a powdering device comprising means 130

for blowing a resist powder against the surface of the plate and at an angle thereto, means for moving the plate relative to the blowing means for progressive powdering across the face of the plate, and an exhaust device for drawing surplus powder from the surface of the plate.

8. In a device for preparing printing plates, a powdering device comprising means for blowing a resist powder against the surface of the plate and at an angle thereto, means for moving the plate relative to the blowing means for progressive powdering across the face of the plate, means for fixing 10 to the surface of the plate the powder remaining upon the plate, and means for turning the plate substantially a quarter turn for the application of powder to the surface thereof transversely of the direction of the 15 previous application of the powder thereto.

9. In a mechanism for preparing printing plates, means for moving a plate from a powdering zone to a heating zone, and means for applying a resist powder to the surface 20 of the plate to be treated, said means comprising a projecting nozzle having a narrow elongated orifice for projecting the powder in a sheet over the surface of the plate.

10. In a mechanism for preparing printing plates, means for moving a plate from a powdering zone to a heating zone, and means for applying a resist powder to the surface of the plate to be treated, said means comprising a projecting nozzle having a narrow 25 elongated orifice for projecting the powder in a sheet over the surface of the plate, and a lip adjacent said orifice for aiding in directing the projecting of the powder over the surface of the plate.

40 11. In a mechanism for preparing printing plates, means for moving a plate from a powdering zone to a heating zone, and means for applying a resist powder to the surface of the plate to be treated, said means comprising a projecting nozzle having a narrow 45 elongated orifice for projecting the powder in a sheet over the surface of the plate, and means for supporting the nozzle adjacent the plate for projecting the powder at an acute 50 angle to the surface of the plate.

12. In a mechanism for preparing printing plates, means for moving a plate from a powdering zone to a heating zone, and means for applying a resist powder to the surface of the plate to be treated, said means comprising a projecting nozzle having a narrow 55 elongated orifice for projecting the powder in a sheet over the surface of the plate, and means for supporting the nozzle adjacent the plate for projecting the powder at an acute angle to the surface of the plate, and an overhanging lip on the nozzle for confining the projected sheet of powder to the proper angle for applying the same to

the parts of the plate surface to be unaffected by the bite.

13. In a mechanism for preparing printing plates, means for moving a plate from a powdering zone to a heating zone, and means for applying a resist powder to the surface of the plate to be treated, said means comprising a projecting nozzle having a narrow elongated orifice for projecting the powder in a sheet over the surface of the plate, and means for adjusting the angular relation 75 of the nozzle and the plate.

14. In a device for preparing printing plates, a support, movable means on the support for moving a plate from a powdering zone to a heating zone, said movable means including a turn-table upon which the plates may rest, means on the support and on the turn-table cooperating to effect a partial turn of the table when the latter is moved from the heating to the powdering zone whereby the successive powdering of the plate may be transversely to the direction of the preceding powdering of the plate.

15. In a device for preparing printing plates, a support, movable means on the support for moving a plate from a powdering zone to a heating zone, said movable means including a turn-table upon which the plate may rest, a grooved latch on the support, a pin on the turn-table and co-operable with the latch when the turn-table is moved from the powdering zone to the heating zone to idly operate the latch and when the turn-table is moved from the heating zone to the powdering zone to cause the 100 pin to ride in the groove of the latch to effect a quarter turn of the table.

16. In a device for preparing printing plates, a support, a carriage movable over the support through powdering, heating and cooling zones and adapted to carry a plate to be treated in said zones, means for supplying air in said cooling zone and including a conduit provided with a control valve, mechanism connected to said valve for operating the same, and means on the carriage for engaging with the mechanism to operate the valves whereby the air may be supplied to said zones when the carriage moves therein and to cut off the air when the carriage is moved therefrom.

17. In a device for preparing printing plates, a support, a carriage movable over the support through powdering, heating and cooling zones and adapted to carry a plate to be treated in said zones, means for supplying air to the powdering and cooling zones comprising discharge outlets extending respectively into said zones, a valve for controlling said outlets, and means connected to the valve for operating the same to open one outlet when closing the other, means on said carriage co-operable with said valve op-

erating means when said carriage is moved from the heating zone to the cooling zone to actuate the valve to open the discharge outlet for the cooling zone whereby air is supplied to cool the plate on the carriage, said means on said carriage also operating when the carriage is moved from the cooling zone to actuate the valve operating means to move the valve to closed position in the discharge outlet for the cooling zone and to open the discharge outlet extending to the powdering zone.

18. In a device for preparing printing plates, a support, a carriage movable over the support through powdering, heating and cooling zones and adapted to carry a plate to be treated in said zones, means for supplying air to said zones and comprising conduits leading to the respective zones and having valves for controlling the passage of air through said conduits, operating mechanism connected to said valves, means on the carriage engageable with said mechanism when the carriage is moved from the heating zone to the cooling zone to operate the same for opening the valve in the conduit to the cooling zone and closing the valve in the conduit to the powdering zone and also closing the valve in the conduit to the heating zone, said means on said carriage also operating said mechanism when the carriage is moved from the cooling zone to the powdering zone to close the valve of the conduit to the cooling zone and opening the conduits to the powdering and heating zones, said means on said carriage being inoperative on the mechanism when the carriage is moved from the powdering zone to the heating zone whereby the conduits to the cooling and heating zones remain respectively closed and open when the carriage is moved from the powdering to the heating zones.

19. In a device for preparing printing plates, a support, a carriage movable on the support from a powdering chamber to a heating space and adapted to carry a plate to be treated in said chamber and space, means for applying powder to the plate in the powdering chamber and comprising a nozzle extending into said chamber adjacent the path of movement of the surface of the plate, and a brush acting upon the surface of the plate when the carriage is moved from the powdering chamber to remove surplus powder from the surface of the plate.

20. In a device for preparing printing plates, a support, a carriage movable on the support from a powdering chamber to a heating space and adapted to carry a plate to be treated in said chamber and space, means for applying powder to the plate in the powdering chamber and comprising a nozzle extending into said chamber adjacent the path of movement of the surface of the plate, a brush acting upon the surface of the

plate when the carriage is moved from the powdering chamber to remove surplus powder from the surface of the plate, a second nozzle having its discharge end adjacent to the surface of the brush and operable to blow off particles of powder adhering to the brush.

21. In a device for preparing printing plates, a support, a carriage movable on the support from a powdering chamber to a heating space and adapted to carry a plate to be treated in said chamber and space, means for applying powder to the plate in the powdering chamber and comprising a nozzle extending into said chamber adjacent the path of movement of the surface of the plate, and a brush acting upon the surface of the plate when the carriage is moved from the powdering chamber to remove surplus powder from the surface of the plate, means for rotating the brush, and a second nozzle having its discharge end adjacent to the surface of the brush and operable to blow off particles of powder adhering to the brush.

22. In a device for preparing printing plates, a support, a carriage movable on the support from a powdering chamber to a heating space and adapted to carry a plate to be treated in said chamber and space, means for applying powder to the plate in the powdering chamber and comprising a nozzle extending into said chamber adjacent the path of movement of the surface of the plate, a brush acting upon the surface of the plate when the carriage is moved from the powdering chamber to remove surplus powder from the surface of the plate, and means for adjusting the relation of the brush to the path of movement of the surface of the plate.

23. In a device for preparing printing plates, a support, a carriage movable on the support from a powdering chamber to a heating space and adapted to carry a plate to be treated in said chamber and space, means for applying powder to the plate in the powdering chamber, a nozzle extending into said chamber adjacent the path of movement of the surface of the plate, a brush acting upon the surface of the plate when the carriage is moved from the powdering chamber to remove surplus powder from the surface of the plate, a second nozzle having its discharge end adjacent to the surface of the brush and operable to blow off particles of powder adhering to the brush, and means for adjusting said second nozzle relative to the surface of the brush.

24. In a device for preparing printing plates, a support, a carriage movable on the support from a powdering to a heating zone and adapted to carry a plate to be treated in said zones, means for applying powder

- to the surface of the plate, a blowing means for projecting the powder upon the surface of the plate, an exhaust device for removing the superfluous powder projected upon the plate, and a reservoir for the powder, said exhaust means conveying the superfluous powder into said reservoir, said blowing means being connected to the reservoir for receiving powder therefrom.
- 10 25. In a device for preparing printing plates, a support, a carriage movable on the support from a powdering to a heating zone and adapted to carry a plate to be treated in said zones, means for applying powder to the surface of the plate, a blowing means for projecting the powder upon the surface of the plate, an exhaust device for removing the superfluous powder projected upon the plate, a reservoir for the powder, said 15 exhaust means conveying the superfluous powder into said reservoir, said blowing means being connected to the reservoir for receiving powder therefrom, and means in the connection between the reservoir and the 20 blowing means for controlling the supply of powder to the latter.
26. In a device for preparing printing plates, a support, a carriage movable on the support from a powdering to a heating zone and adapted to carry a plate to be treated in said zones, means for applying powder to the surface of the plate, a blowing means for projecting the powder upon the surface of the plate, an exhaust device for removing the superfluous powder projected upon the plate, a reservoir for the powder, said exhaust means conveying the superfluous powder into said reservoir, said blowing means being connected to the reservoir for receiving powder therefrom, and means in said reservoir for aiding in distributing the powder therein.
27. In a device for preparing printing plates, a support, a carriage movable on the support from a powdering to a heating zone and adapted to carry a plate to be treated in said zones, means for applying powder to the surface of the plate, a blowing means for projecting the powder upon the surface of the plate, an exhaust device for removing the superfluous powder projected upon the plate, a reservoir for the powder, said exhaust means conveying the superfluous powder into said reservoir, said blowing means being connected to the reservoir for receiving powder therefrom, and a series of baffles in the reservoir for distributing the powder therein.
28. In a device for preparing printing plates, means for circulating powder used as a resist on plates to be treated, a plate supporting means adapted to be located in the path of circulation of the powder, means for controlling the circulation of said powder, said circulating means comprising a powder reservoir having pervious portions through which air may pass but which retain the powder.
29. In a device for preparing printing plates, means for circulating powder used as a resist on plates to be treated, a plate supporting means adapted to be located in the path of circulation of the powder, means for controlling the circulation of said powder, said circulating means comprising a powder reservoir having a series of pervious pockets for permitting the escape of air and the retention of the powder.
30. In a device for preparing printing plates, means for circulating powder used as a resist on plates to be treated, a plate supporting means adapted to be located in the path of circulation of the powder, means for controlling the circulation of said powder, said circulating means comprising a powder reservoir having a series of pervious pockets for permitting the escape of air and the retention of the powder, and means for shaking the pockets for the shaking off of the powder adhering to the same.
31. In a device for preparing printing plates, means for circulating powder used as a resist on plates to be treated, a plate supporting means adapted to be located in the path of circulation of the powder, means for controlling the circulation of said powder, said circulating means comprising a powder reservoir having a series of pervious pockets for permitting the escape of air and the retention of the powder, and means connected to the pockets and movable to contract and extend the pockets with a snap action whereby the powder adhering to the walls of the pockets may be forcibly cast therefrom.
32. In a device for preparing printing plates, means for circulating powder used as a resist on plates to be treated, a plate supporting means adapted to be located in the path of circulation of the powder, means for controlling the circulation of said powder, said circulating means comprising a powder reservoir, feeding means in the reservoir operable to feed the collected powder therein to the controlling means.
33. In a device for preparing printing plates, means for circulating powder used as a resist on plates to be treated, a plate supporting means adapted to be located in the path of circulation of the powder, means for controlling the circulation of said powder, said circulating means comprising a powder reservoir, feeding means in the reservoir operable to feed the collected powder therein to the controlling means, said feeding means having reverse feeding elements for stirring the powder and preventing packing thereof.
34. In a device for preparing printing plates, means for circulating powder used

- as a resist on plates to be treated, a plate supporting means adapted to be located in the path of circulation of the powder, means for controlling the circulation 5 of said powder, said circulating means comprising a powder reservoir, feeding means in the reservoir operable to feed the collected powder therein to the controlling means, said feeding means comprising feed screw 10 for feeding the powder in one direction and a reverse feed portion at the end of the feed screw for stirring the powder and preventing packing thereof.
35. In a device for preparing printing plates, means for circulating powder used as a resist on plates to be treated, a plate supporting means adapted to be located in the path of circulation of the powder, means for controlling the circulation of said powder, said circulating means comprising a powder reservoir, feeding means in the reservoir operable to feed the collected powder therein to the controlling means, said feeding means comprising a feed screw for feeding 20 the powder in one direction and a reverse feed portion at the end of the feed screw for stirring the powder and preventing packing thereof, said reverse feed portion having notches for the passage there- 25 through of the powder in a direction opposite to the action of the reverse feed portion whereby the powder is stirred and prevented from packing but at the same time progresses through the notches for circulation.
- 30 35. In a device for preparing printing plates, a movable support for supporting plates to be treated and comprising a turn-table upon which the plate may rest when powder is supplied to the surface of the plate, means for turning the table for supplying of the powder at a different direction than previously.
36. In a device for preparing printing plates, a movable support for supporting plates to be treated and comprising a turn-table upon which the plate may rest when powder is supplied to the surface of the plate, means for turning the table for supplying of the powder at a different direction than previously, a race-way on the support and rollers carried by the table and cooperating with the race-way for ready turning of the table on the support.
37. In a device for preparing printing plates, a movable support for supporting plates to be treated and comprising a turn-table upon which the plate may rest when powder is supplied to the surface of the plate, means for turning the table for supplying of the powder at a different direction than previously, a race-way on the support and rollers carried by the table and cooperating with the race-way for ready turning of the table on the support.
38. In a device for preparing printing plates, a movable support for supporting plates to be treated and comprising a turn-table upon which the plate may rest when powder is supplied to the surface of the plate, means for turning the table for supplying of the powder at a different direction than previously, said table and support having cooperable locking elements for holding the table in turned relation.
39. In a device for preparing printing plates, a movable support for supporting plates to be treated and comprising a grate upon which the plate may rest when powder is supplied to the surface of the plate, the surplus powder being capable of passing through the openings of the grate, a turn-table upon which the plate may rest when powder is supplied to the surface of the plate, means for turning the table for supplying of the powder at a different direction than previously, said table and support having cooperable recesses and spring pressed balls for normally holding the table in turned relation to the support.
40. In a device of the character disclosed, a heating chamber, movable means for carrying a plate to be treated and movable into and from said chamber, heating means in the chamber located to transmit heat to the powdered surface of the plate when carried into the chamber, means engaged by the movable means when it has moved into the chamber to effect transmission of heat from the heating means and when starting to move from said chamber to effect a cutting-off of said heat.
41. In a device of the character disclosed, a heating chamber, movable means for carrying a plate to be treated and movable into and from said chamber, heating means in the chamber located to transmit heat to the surface of the plate when carried into the chamber, and comprising burners, a pilot light in the chamber arranged to ignite the burners, means for supplying a combustible medium to the burners, means on the supplying means and engageable by the movable means when moved into the chamber to effect the supply of the medium to the burners and when the movable means is moved from the chamber to effect a cut-off of said medium.
42. In a device of the character disclosed, a heating chamber, means for supporting a plate therein for treatment of the surface thereof, burners located above said surface of said plate, means for supplying a supporter of combustion to said burners and over said plate, said chamber being open at the lower portion thereof for the free exit of the products of combustion.
43. A method of treating printing plates or the like, comprising the steps of projecting a sheet of resist material upon the surface of a plate and at an acute angle to said surface, subjecting said surface of said plate to heat for a short period of time sufficient to only heat and fix the resist material, and subjecting the surface of the plate to a stream of air for cooling the same.
44. A method of treating printing plates or the like, comprising the steps of circulating a stream of air and resist material, and moving a plate to be treated through said

stream for the application of material to the surface of said plate, and fixing the material on said surface of the plate.

45. A method of treating printing plates or the like, comprising the steps of circulating a stream of air and resist material, and moving a plate to be treated through said stream for the application of material to the surface of said plate, controlling the circulation to effect a projection of said material upon said surface of the plate while the plate is being moved through the path of circulation, and for cutting off the circulation of the material when the plate has moved out of said path, and then fixing the material on said surface.

46. A method of treating printing plates or the like, comprising the directing of a stream of air and resist powder upon the surface of a plate to be treated, applying a brush to the surface of the plate for removing superfluous particles of the powder, and then fixing the remaining powder on said surface of the plate.

47. In a device for preparing printing plates, a support, a carriage movable on the support from a powdering to a heating zone and adapted to carry a plate to be treated in said zones, means for applying powder to the surface of the plate and comprising a blowing means for projecting the powder upon the surface of the plate, an exhaust device for removing the superfluous powder projected upon the plate, a reservoir for the powder, said exhaust means conveying the

superfluous powder into said reservoir, said blowing means being connected to the reservoir for receiving powder therefrom, and means in the connection between the reservoir and the blowing means for controlling the supply of powder to the latter, said connection having a relief valve for the inlet of air for clearing the passages in said connection, and blowing means of powder when the control means is closed.

48. In a device for preparing printing plates, means for circulating powder used as a resist on plates to be treated, a plate supporting means adapted to be located in the path of the circulation of the powder, means for controlling the circulation of the powder, and air relief means connected to the circulating means and operating to permit entry of air to clear the circulating means of powder when control means is operated to stop circulation.

49. In a device for preparing printing plates, means for circulating powder used as a resist on plates to be treated, a plate supporting means adapted to be located in the path of the circulation of the powder, means for controlling the circulation of the powder, and an air relief valve connected to the controlling means for admitting air into the circulating means when the controlling means is shut off.

In witness whereof, I hereunto subscribe my name to this specification.

HERBERT H. POWERS.
